UNITED STATES PATENT OFFICE

119,788

DESIGN FOR A BASEBOARD REGISTER

Carl S. Lundgren, Muskegon, Mich., assignor to
Air Control Products, Inc., Muskegon, Mich., a
corporation

Application November 13, 1939, Serial No. 88,241

Term of patent 7 years

To all whom it may concern:

Be it known that I, Carl S. Lundgren, a citizen of the United States, residing at Muskegon, in the county of Muskegon and State of Michigan, have invented a new, original, and ornamental Design for a Baseboard Register, of which the following is a specification, reference being had to the accompanying drawing, forming a part thereof.

In the drawing:

Figure 1 is a front elevational view of a baseboard register showing my design; and

Figure 2 is a side elevational view thereof.

I claim:

The ornamental design for a baseboard register, as shown.

CARL S. LUNDGREN.
